UNITED STATES PATENT OFFICE

LOCKWOOD MYRICK, JR., OF HONOLULU, TERRITORY OF HAWAII

INTERNAL COMBUSTION ENGINE

Application filed July 23, 1928. Serial No. 294,711.

My invention relates to improvements in internal combustion engines, and it consists in the combinations, constructions, and arrangements hereinafter described and claimed.

An object of my invention is to provide an engine to be used in power houses, in which a liquid replaces the conventional solid piston. The device primarily consists of an oscillating annular ring not quite half full of some liquid such as water. This liquid could be molten metal or other chemically stable substance.

The liquid within the ring forms two compartments, each of which acts as a cylinder for receiving the gas. The engine works on the two-cycle principle and the cylinders are therefore scavenged with fresh air after each exhaust and prior to the intake of new

gas. The ring oscillates during its operation, and I operatively connect it to a crank shaft so that the latter will be turned continuously in one direction while the engine is operating. The engine has many advantages which will be set forth after the construction and operation have been described, because these advantages will be more apparent after a more full understanding of the engine is had.

Other objects and advantages will appear in the following specification, and the novel features of the device will be particularly pointed out in the appended claims.

My invention is illustrated in the accompanying drawings forming a part of this application, in which

Figure 1 is a side elevation of the engine;

Figure 2 is a section along the line 2—2 of Figure 1;

Figure 3 is a vertical section through the ring;

Figure 4 is a section along the line 4—4 of Figure 3; and

Figure 5 is a section along the line 5—5 of Figure 4.

In carrying out my invention, I provide a supporting base indicated generally at 1 (see Figure 1). This base has two bearings 2 and 3. In the bearing 2 I mount a shaft

4 upon which is mounted a ring 5 of the shape shown in Figure 3.

Figures 3 and 4 show the construction of the ring 5 and its associate mechanism. It will be noted that the ring is continuous with the exception of a small partition 6. The partition 6 forms the head of two compression chambers 7 and 8, and these chambers are kept separated from each other by a liquid 9. The ring stands in a vertical plane, and, therefore, the liquid will assume the position shown in Figure 3. I have shown the level of the liquid as being higher on the left-hand side of the ring in order to illustrate the operation of the machine. This feature will be more clearly set forth as the specification proceeds.

The shaft 4 is rigidly mounted in the bearing 2, and the ring 5 oscillates upon this shaft. Bearings 10 support the ring (see Figure 4).

The ring has two intake valves 11 and 12 disposed at the heads of the chambers 7 and 8. Springs 13 and 14 urge these valves into closed position. Arms 15 and 16 move the valves into open position at predetermined intervals. The arms are mounted upon shafts 17 and 18 (see Figure 3), and Figure 1 shows how the shafts carry arms 19 and 20 that are actuated by cam followers 21 and 22. In Figure 4 I show the shaft 18, arm 20 and cam follower 22 as being operatively connected to a cam 23.

The cam follower 21 is operatively connected to a cam 24 that is integral with the cam 23.

I also provide exhaust valves 25 and 26 (see Figure 3). These valves are disposed a slight distance away from the intake valves and are arranged in a position to permit the exhaust gases to pass thereby, and also to prevent any appreciable amount of air from escaping when the cylinders are scavenged. The valves 25 and 26 are spring pressed (note the springs 27 and 28). These springs yieldingly hold the valve stems in contact with arms 29 and 30. The arms in turn are carried by shafts 31 and 32, and Figure 4 shows how these shafts carry cam followers 33 and 34 that are in contact with cams 35 and 36

respectively. It is obvious that other types of valves may be used; but I have found that the poppet valve is the most logical.

All four of the cams 23, 24, 35 and 36 are connected together and are shown in Figure 5. The high points of these cams are arranged to cause the intake and exhaust valves to open and close at the proper time intervals. The four cams are rotatively mounted on the shaft 4 and have a sprocket wheel 37 integral therewith. Around this sprocket I dispose a chain 38, and this chain is passed around a sprocket wheel 39 (see Figure 2), the latter being mounted on a worm 42. The worm is mounted upon a spline 41 forming a part of a crank shaft 40, which in turn is rotatively mounted in the bearings 3.

I provide means for advancing or retarding the cams, and this is shown in Figure 2. The splined portion 41 of the crank shaft 40 carries the worm 42.

The splined portion 41 prevents rotative movement between the worm 42 and the portion but permits longitudinal movement. The sprocket 39 is mounted upon the worm 42. It will be seen from this construction that the movement of the worm along the spline will rotate the sprocket 39 with respect to the crank shaft 40 and in this way vary the timing of the valves. I show the worm 42 as being provided with an annular groove 43 in which a finger 44 rides. This finger may be manually moved and held in adjusted position by means not shown. The moving of the finger will vary the timing mechanism of the valves.

I will now describe the mechanism for scavenging the chambers 7 and 8. In Figure 4 I show a fan 45 rotated by a sprocket 46 which in turn is driven by a sprocket chain 47, a sprocket wheel 48 (see Figure 2) and the crank shaft 40. The fan 45 is housed at 49 and a conduit 50 leads therefrom to a passageway 51 (see Figure 3). Air is being forced through this conduit so long as the engine operates, and this air is delivered into the chambers 7 and 8 depending upon whether the valve 11 or valve 12 is open.

The means for delivering a combustible gas to the chamber is also shown in Figure 3. Gas flows through either of the two pipes 52 and 53 to a common pipe 54. Valves 55 and 56 control the flow of gas and in turn are controlled by the arms 15 and 16. Any other suitable construction which will feed gas into the passageway 51 at the proper time intervals will answer the purpose. The valves 55 and 56 are so connected with the arms 15 and 16 as to open after the valves 11 and 12 have first been opened a short time.

The means for delivering liquid to the interior of the ring 5 to replenish the supply lost through evaporation, consists of a funnel 57 (see Figure 4), a passageway 58 in the shaft 4, a pipe 59 leading from the pas-

sageway into a second funnel 60 (see Figure 3) and a conduit 61 leading from the second funnel into the interior of the ring 5. A valve 62 permits the fluid to pass only in one direction.

The ring 5 oscillates upon the shaft 4, and this rocking motion is converted into a uni-directional rotary motion by means of connecting rods 63 which have their free ends connected to the ring and to the crank shaft 40. A fly wheel 64 may be used for providing a uniform movement to the crank shaft 40.

From the foregoing description of the various parts of the device, the operation thereof may be readily understood.

Let us suppose that the liquid has risen in the compression chamber 7 and has compressed the air or gas mixture and that this has been ignited by the spark plug 65. The force of explosion will drive the liquid down and around to the other side and at the same time will drive the cylinder or ring 5 in the opposite direction. During a little more than a half of the stroke, the exhaust valve 26 of the chamber 8 is kept open and the burnt gases in this chamber are expelled by the rising liquid.

As soon as the pressure on this side, i. e., the pressure in the chamber 8, is down nearly to atmospheric pressure, the intake valve 12 opens and fresh air from the passageway 51 is blown in under pressure from the air compressor or fan 45. This air scavenges the cylinder or chamber 8 of burnt gases above the exhaust valve 26.

Just before the liquid reaches the exhaust valve, the latter closes, and very shortly later the intake valve 12 also closes. The intake valve 12, however, has remained open long enough to permit gas to flow from the passageway 51 into the chamber 8. Gas is admitted to the passageway 51 by the opening of the valve 56 (see Figure 3).

When the pressure in the chamber 8 is sufficiently high, the mixture is electrically ignited by the spark plug 66. The resulting explosion soon stops the flow of liquid into the chamber 8 and sends it in the opposite direction. The same cycle is then repeated for the chamber 7.

It will be seen from this that each end of the cylinder or ring 5 is a two-cycle engine, the two together being equivalent to four four-cycle cylinders. The internal friction of the device is low because the friction of a moving liquid should be much less than that of a solid. There are two explosions for each complete oscillation, and, therefore, the device will deliver considerable power.

Since the cylinder or ring 5 is half the time moving in the same direction as the cams 23, 24, 35 and 36 and the other half of the time moving in the opposite direc-

tion, the cams for the valves of one chamber would have to be much sharper than those for the others.

With an oscillation of 90° , there is a relative motion of the cams to the cylinders of 90° during one oscillation and 270° during the next, so that the cams for one side would have to be approximately three times as sharp as the cams for the other, the difference between the two sets of cams being less than this for those sections of the cams either opening the valves or allowing them to close while the cylinders are moving at an angular velocity below their average. The difference is greater for those sections of the cams either opening the valves or allowing them to close while the cylinders are moving at an angular velocity above their angular velocity above their average. For purposes of simplicity, however, the cams in Figures 4 and 5 have been drawn as if the cylinders were at all times moving at a constant angular velocity.

At this point it is well to note the three positions into which the ring 5 moves. The broken line A in Figure 1 represents a neutral position, the line B, the extreme left-hand position and the line C, the extreme right-hand position. The ring 5 swings through an arc of 90° , altho this could be varied. This swing is sufficient to throw the connecting rods 63 a distance far enough to swing the crank shaft 40 through one-half of a circle. The return movement of the ring 5 swings the crank shaft through the other half of the circle. In this way an oscillating movement of the ring will give a uni-directional drive to the crank shaft.

In starting the engine, if fuel and air were mixed before entering the cylinder, the starting would occasion no difficulty.

The engine needs no water cooling jacket because the water 9 reaches all parts of the cylinder and no other cooling is therefore necessary. The heat which in other engines is lost is in this case used to generate steam and thus to increase the pressure on the power stroke. Since, however, there is no oil film to be maintained, the operating temperature need not be limited to the boiling point of the water or to the flash point of some oil; hence some other liquid with a high boiling point such as molten aluminum, cryolite, or even sodium chloride could be used instead. In fact, the only limit to the operating temperature is the breaking point of the cylinder walls and not the breaking point of an oil film. This feature of operating at a very high temperature justifies an expectation of exceptional efficiency.

The engine has a short intake and a very long expansion. The drawings shows the expansion as being almost three times the length of the intake, and this could be greatly increased if desired. This point is also con-

ducive to high efficiency. In Citroen's variable stroke engine in which the power stroke is just twice that of the intake, 25% less fuel is needed for the same horsepower as when the power stroke is the same as the intake 70 stroke. The present engine operates at a very high compression which would permit it to be worked in the same manner as a Diesel engine. Unlike the large Diesel engine, however, there is no problem in the present engine of cooling the piston and no need of allowing for piston expansion. There would therefore be no loss of compression when the engine is cold. The seal of compression would be absolutely perfect because a liquid 75 is used. It would also be unaffected by the wear of the cylinder walls.

Considerable power is lost in the Diesel engine in compressing the air. In the present invention, the compression is done by the 80 liquid and not by the crank shaft. Instead of reversing the direction of the cylinder when the liquid is highest in it, it could be reversed at the instant the pressure of the compressed air equals the pressure in the expanding gases. That is to say, the working 85 pressure on either cylinder head, and hence on the crank shaft, would be from the instant the pressure in one compression chamber should exceed the pressure in the other compression chamber, to the instant the pressure in the first chamber should be exceeded by the pressure in the other chamber. It would therefore be as great as possible.

Compression in the present invention occurs while the piston is moving at its maximum velocity. It therefore takes a far shorter time and allows much less heat to be wasted than is true in the standard engine. Again, the torque obtained in the ordinary 100 gas engine during the second half of the power stroke is much less than that obtained during the first half, since the pressure of the exploding gas is much less: the piston takes as long to move half way when the pressure 105 is low as it does when the pressure is high. In the present invention, the piston moves with continuously increasing velocity during the whole of the power stroke and therefore completes the second half of its power in a 110 far shorter time. Expansion is most rapid when the pressure is lowest, hence the torque should be remarkably smooth.

Furthermore, the fuel could be injected, if the Diesel principle is used, the instant the 115 pressure in the compression chamber equals the pressure of the expanding gases, not when the pressure reaches four to five hundred pounds. This change would give a longer time for combustion. If the liquid were 120 water, there might be no advantage in introducing the fuel so early, but if it were molten metal or cryolite, the temperature of the air would be high enough to start combustion before the pressure had become great. This 125

longer time should mean more complete combustion and also an excess of air less great than is required in the conventional Diesel engine. This would result in a higher mean effective pressure during the power stroke.

It should also be noted that the fuel could be pulverized coal. Hitherto this kind of fuel has not been successfully used in internal combustion engines because the fuel is not only gritty in itself but leaves a gritty ash, both of which cut through the oil film and quickly score the cylinder walls. This difficulty would not exist in the present invention because the piston requires no lubrication. The valves would work efficiently because there is no oil to cause the pulverized coal to stick to them.

Summing up, high efficiency should be had for the following reasons:

- 20 1. Low internal friction;
  2. Low cooling losses;
  3. High operating temperature (if some other liquid than water is used);
  4. Very long expansion;
  - 25 5. High compression;
  6. Perfect seal for compression;
  7. Less power lost in compressing; and
  8. More perfect combustion and higher mean effective pressure if the ignition is of
- 30 the Diesel type.

It should also be noted that the engine could be used as a steam engine or for the expansion of any other gas compressed externally to the engine.

35 Although I have shown and described one embodiment of my invention, it is to be understood that the same is susceptible of various changes, and I reserve the right to employ such changes as may come within the scope of

40 the appended claims.

I claim:

- 45 1. An engine comprising a ring-shaped cylinder having a transverse partition forming two cylinder heads, and a fluid in said ring and constituting a piston common to both cylinder heads.
- 50 2. An engine comprising a shaft, a ring-shaped cylinder oscillatable thereon, a partition, a fluid constituting a moveable piston common to both cylinder heads formed by said partition.
- 55 3. An engine comprising a shaft, a ring-shaped cylinder oscillatable thereon, a partition, a fluid constituting a moveable piston common to both cylinder heads formed by said partition, and intake and exhaust valves disposed adjacent to each end of said ring.
- 60 4. An engine comprising a shaft, a ring-shaped cylinder oscillatable thereon, a partition forming the ring into two cylinder heads, a fluid in said ring and constituting a moving piston common to both cylinder heads, means for delivering gases to and for
- 65 5. An engine comprising a circular-shaped cylinder, a fluid therein and constituting a moveable piston, intake valves disposed at the ends of said cylinder, exhaust valves disposed in said cylinder and means for initially feeding fresh air and then gas through said intake valves while they are open.
6. In an engine, a circular-shaped cylinder, valves disposed adjacent to each end of the cylinder, a fluid in said cylinder and constituting a piston, means for exploding gases in each end of said cylinder for causing it to oscillate, and cams for opening said valves.
7. An engine comprising a circular-shaped cylinder, a fluid in said cylinder and constituting a piston, means for exploding gases in each end of said cylinder for causing it to oscillate, a crankshaft, and means connecting said cylinder with said crankshaft so as to cause the latter to rotate continuously in one direction as said cylinder is oscillated.
8. In an engine, a fixed shaft, an arcuate-shaped cylinder oscillatable thereon, a fluid in said cylinder and constituting a piston, means for alternately exploding a combustible charge in each end of the cylinder, a funnel communicating with said cylinder, a check valve for the funnel, and a fluid conduit leading through the shaft and emptying into the funnel.

shaft and connections between said crank shaft and said ring.

5. An engine comprising a circular-shaped cylinder, a fluid therein and constituting a moveable piston, intake valves disposed at the ends of said cylinder, exhaust valves disposed in said cylinder and means for initially feeding fresh air and then gas through said intake valves while they are open.

6. In an engine, a circular-shaped cylinder, valves disposed adjacent to each end of the cylinder, a fluid in said cylinder and constituting a piston, means for exploding gases in each end of said cylinder for causing it to oscillate, and cams for opening said valves.

7. An engine comprising a circular-shaped cylinder, a fluid in said cylinder and constituting a piston, means for exploding gases in each end of said cylinder for causing it to oscillate, a crankshaft, and means connecting said cylinder with said crankshaft so as to cause the latter to rotate continuously in one direction as said cylinder is oscillated.

8. In an engine, a fixed shaft, an arcuate-shaped cylinder oscillatable thereon, a fluid in said cylinder and constituting a piston, means for alternately exploding a combustible charge in each end of the cylinder, a funnel communicating with said cylinder, a check valve for the funnel, and a fluid conduit leading through the shaft and emptying into the funnel.
